FLASH-LIGHT.

1,239,078.

Specification of Letters Patent.

Patented Sept. 4, 1917.

Application filed November 19, 1915. Serial No. 62,302.

To all whom it may concern:

Be it known that I, BERNARD BENEDICT, a citizen of the United States, and a resident of New York city, in the county of Bronx 5 and State of New York, have invented certain new and useful Improvements in Flash-Lights, of which the following is a specification.

The invention pertains more particularly to a novel construction of flash light adapted to be carried in the pocket and by preference the casing of this flash light will be in the similitude of a watch case, so that the article as a whole may have the appearance 10 of a watch and, if desired, carried in the vest pocket and be held by a customary watch chain or fob. The casing of the flash light will be composed of two substantially equal sections which may be opened outwardly from each other and which, when together, will form between them a chamber 15 adapted to receive a two cell battery with the appropriate conductors. The casing will preferably be of metal and be provided with a stem in the similitude of the stem of a watch case and containing a socket in which will be applied the electric lamp, and the said stem will also preferably be provided with a ring to which a chain may be connected. 20 Upon the edge of the casing of the flash light is provided a finger piece for making and breaking the circuit. The article as a whole is intended to convey the impression of a watch and to afford a novel construction 25 of flash light which may be conveniently carried in the pocket and conveniently used.

The invention will be fully understood from the detailed description hereinafter 30 presented, reference being had to the accompanying drawings, in which:

Figure 1 is a view, partly in section, showing the flash light of my invention with the two sections of the casing opened outwardly 35 from each other;

Fig. 2 is a section through the same, taken on the dotted line 2—2 of Fig. 1;

Fig. 3 is a slightly enlarged top view of my flash light, the casing sections being 40 shown as closed together and the ring as turned to one side so as to more fully disclose the electric lamp;

Fig. 4 is a section through the same, taken on the dotted line 4—4 of Fig. 3;

Fig. 5 is an interior elevation, partly

broken away, of one section of a modified construction of flash light embodying my invention;

Fig. 6 is a corresponding view of the same, but with the battery cells and their 60 supporting frame removed;

Fig. 7 is a slightly enlarged vertical section through the modified flash light as a whole taken on the dotted line 7—7 of Fig. 5;

Fig. 8 is a detached elevation of the supporting frame for the battery cells;

Fig. 9 is a slightly enlarged transverse section through a portion of the casing taken on the dotted line 9—9 of Fig. 6, and

Fig. 10 is a like view, taken on the dotted line 10—10 of Fig. 6.

In the drawings, referring to Figs. 1 to 4 inclusive, 10 designates the flash light casing as a whole, 11 the stem creating a socket 12 for the lamp 13, and 14 a ring swiveled to said stem and adapted to receive the end of a chain. The casing 10 is formed of two substantially equal metallic shells 15, 16, which are hinged together, as at 17, and 80 form within them a receiving chamber for the battery cells 18. The shells 15, 16 are preferably circular in edge outline and sufficiently dished within such outline to create the battery receiving chamber, and in 85 general respects the said sections 15, 16 form a casing in the similitude approximately of a watch case. The stem 11 is of sheet metal and has a lower threaded inner portion and an open top, as shown in Fig. 2, 90 and it is carried wholly by the casing section 15. The casing section 16 is recessed, as at 18*, to fit around the lower edge of the stem 11, and said section 16 may be provided with any suitable catch 19 for releasably connecting it with the section or shell 15.

Within the shell or section 15 is secured a partition 20 upon which the battery cells 18 may be placed, said cells being inclosed in 100 a carton 21 insulating their walls from each other and from the shell 15. The cells 18 are parallel with each other and extend transversely of the shell 15, with their positive and negative poles oppositely or reversely arranged, and the positive pole 22 of one cell 18 is connected by a conducting wire 23 with the negative pole of the other cell 18, and said other cell 18 has its positive pole 24 in electrical contact with a con- 110

tacting spring 25, which is secured to the shell 15, as shown in Fig. 1. The negative pole of the upper cell 18 has secured to it a conducting contact spring 26, which extends transversely of the casing 10 in proximity to a non-conducting finger 27 carried by a slide 28 to which is secured a thumb piece 29, the slide 28 being at the inner side of the rim of the shell 15 and the thumb piece 29 being at the outer side of said rim, and the slide and thumb piece being connected together by a rivet extending through a slot formed in said rim and allowing said slide and thumb piece to have a movement along said rim for making and breaking the circuit through the lamp. The non-conducting finger 27 is immediately above the upwardly deflected free end of the spring 26, and said spring extends transversely below the terminal 30 of the lamp 13, the other terminal of said lamp being in electrical connection with the stem 11 and shell or section 15. The circuit is made or broken at the terminal 30 of the lamp 11 by the spring 26, and when the thumb piece 29 is in the position illustrated in Fig. 1, it and the slide 28 holds the finger 27 in a position which causes it to prevent the free portion of the spring 26 from moving upwardly to engage the terminal 30, but when the thumb piece 29 and slide 28 are moved upwardly toward the stem 11, the finger 27 is carried in a direction from the free end of the spring 26 and at such time said spring 26 of its own resiliency will move upwardly into contact with the terminal 30 of the lamp, thereby completing the circuit and lighting the lamp, the circuit being from the terminal 30 and spring 26 through the shell of the upper battery cell 18 to the positive pole 22 of said cell, thence through the conductor 23 to the negative pole of the lower battery cell 18 and thence through the positive pole 24 of said cell and spring 25 to the shell 15 and thence through the stem 11 to the other terminal of the lamp 13. When therefore the slide 28 and thumb piece 29 are moved in one direction, they permit the automatic electrical connection of the spring 26 with the terminal 30 of the lamp, the circuit being completed thereby, and when the slide 28 and thumb piece 29 are moved in the reverse direction, the finger 27 carried by the slide moves the spring 26 from its engagement with the terminal 30 and acts as an obstruction to prevent said spring from moving into electrical connection with said terminal 30.

It will be seen from the foregoing description taken in connection with the drawing that I have produced a very efficient and simple form of pocket flash light in the similitude of a watch case, the chamber within the casing of the flash light serving to receive the battery cells and the stem 11

affording a suitable socket for the lamp bulb and its parts.

In Figs. 5 to 10 inclusive I illustrate a modified form of my invention in which 40 designates the exterior casing as a whole, 70 41 the stem creating a socket for the lamp, and 42 a ring swiveled to said stem and adapted to receive the end of a chain or the like. The casing 10 is formed of two substantially equal shells 43, 44 which form 75 within them a receiving chamber for the battery cells 45, 46. The shells 43, 44 are circular in edge outline and in general respects resemble the shells 15, 16, shown in Figs. 1 to 4 inclusive. In this instance the 80 shells 43, 44 are not hinged together, but snapped at their edges one upon the other whereby they become detachably connected together and may be opened outwardly from each other. The stem 41 is the same as the 85 stem 11, shown in Figs. 1 and 2 and is carried by the shell 43 and receives the lamp in the same manner that the stem 11 receives the lamp 13. The cells 45, 46 are parallel with each other, with oppositely arranged poles 90 and supported within an opening 47 formed in a non-conducting partition 48 which fits within the shell 43. The partition 48 is formed of vulcanite or other suitable non-conducting material and it carries a contact spring 49 having two ends, one engaging the negative pole of the cell 45 and the other the positive pole of the cell 46. The partition 48 also carries a conducting or contact spring having one arm 50 in normal engagement with the central terminal 51 of the lamp and its other arm 52 in permanent engagement with the positive pole 53 of the battery cell 45. The shell 43 is of metal and the other lamp terminal is in electrical connection with it, and therefore in order to complete the circuit through the lamp and battery cells it will be necessary for the negative pole of the lower battery cell 46 to be brought within the electric circuit, and to this end I provide a switch 54 in the form of a leaf spring having one end connected with an exposed slide or thumb piece 55 and its other end in convenient relation to the negative pole of the battery cell 46. The switch 54 extends along the rim of the casing section 43 in contact therewith and is at its free portion curved inwardly toward the cell 46, and the said casing section 43 is formed at the outer side of said switch 54 with a projection 56 which serves, when the switch is moved downwardly and caused to ride against it, to force the free end of the spring inwardly against the cell 46. When the switch 54 is in the position shown in 115 Figs. 5 and 6, the free end thereof is not in contact with the cell 46, but when the thumb piece or slide 55 is moved downwardly along the edge of the casing section 43, said switch is caused to move down- 120

wardly and by reason of its curvature and the presence of the projection or stud 56 passes inwardly, at its free end, into engagement with the negative end of the battery cell 46, thereby completing the circuit through the lamp, the circuit being from the lamp terminal 51 and arms 50, 52 to to the positive pole of the cell 45, thence through the spring 49 from the negative 10 pole of the cell 45 to the positive pole of the cell 46 and thence through the switch 54 to the casing section 43, stem 41 and that terminal of the lamp engaging said stem. When it is desired to break the circuit and extinguish the lamp, the slide or thumb piece 55 is moved upwardly toward the stem 41, thereby withdrawing the spring 54 from engagement with the battery cell 46.

In the construction shown in Fig. 1, the 20 switch spring 26 automatically engages the lamp terminal 30 when the thumb piece 29 and slide 28 are moved to permit that result, while in the construction shown in Figs. 5 and 6 the circuit is made by manually moving the switch 54 into engagement with the 25 battery cell 46.

In both forms of the invention the flash light casing is in the form of a watch case and the lamp is carried within what, in a 30 watch case, might be called the stem. The constructions presented by me are entirely efficient in use and in each instance the casing conveniently receives the battery cells and parts necessary for making and breaking 35 the circuit.

What I claim as my invention and desire to secure by Letters-Patent, is:

1. A pocket electric light comprising an electrically conductive casing including two 40 shallow matching shells adapted to be opened one from the other and one of which carries on its side edge a socket for holding a miniature electric lamp having one terminal extended within the casing, a battery 45 within the casing, means for electrically connecting one pole of the battery with the casing, a spring switch connected with the opposite pole of the battery, and manually operative means on the edge of the casing 50 for controlling the action of said spring switch, said spring switch being adapted when unrestrained to engage the said lamp terminal, and said manually operative means having a non-conducting member extending 55 within the casing for engaging said spring switch and holding it out of contact with the lamp terminal.

2. A pocket electric light comprising a battery-containing casing having opposite 60 circular side parts one of which is adapted to be opened, a stem-forming lamp socket projecting radially from the edge of said casing and adapted to receive an electric lamp, a ring pivoted in the projecting lamp 65 socket, a circuit-controlling spring member

adapted when unrestrained to maintain the circuit in closed condition, and a manually actuatable member for holding said spring member at the open circuit position.

3. An electric flash light comprising a 70 casing composed of two shallow matching circular shells adapted to be opened one from the other and one of which carries on its side edge a socket adapted to receive a miniature electric lamp bulb, a battery within 75 said casing having one pole in electric connection with the casing, which is of conducting material, a spring switch connected with the other pole of the battery and adapted when unrestrained to engage one lamp 80 terminal, and manually operative means on the edge of the casing for controlling said spring switch, said manually operative means including a non-conducting member extending within the casing for engaging 85 said spring switch and holding it out of engagement with the lamp terminal.

4. An electric flash light comprising a casing composed of two shallow matching shells adapted to be opened one from the 90 other and one of which carries on its side edge a socket holding a miniature electric lamp bulb having one terminal extended within said casing, a battery within said casing comprising a plurality of cells in side 95 by side relation, means for electrically connecting one pole of one of said cells with the casing, which is of conducting material, a spring switch connected with the opposite pole of another of said cells, conducting 100 means connecting the other opposite poles of said cells together, and manually operative means on the edge of the casing for controlling the action of said spring switch.

5. An electric flash light comprising a 105 casing composed of two shallow matching shells adapted to be opened one from the other and one of which carries on its side edge a socket holding a miniature electric lamp bulb having one terminal extended 110 within said casing, a battery within said casing comprising a plurality of cells in side by side relation, means for electrically connecting one pole of one of said cells with the casing, which is of conducting material, 115 a spring switch connected with the opposite pole of another of said cells, conducting means connecting the other opposite poles of said cells together, and manually operative means on the edge of the casing for controlling the action of said spring switch, said 120 spring switch being adapted when unrestrained to engage the said lamp terminal, and said manually operative means being a slide having a non-conducting member extending within the casing for engaging said 125 spring switch and holding it out of circuit.

6. A pocket electric light comprising an electrically conductive casing including two shallow matching shells adapted to be 130

opened one from the other and one of which carries on its side edge a socket for holding a miniature electric lamp having one terminal extended within said casing, a battery within the casing comprising a plurality of cells in side by side relation with their poles arranged in reverse relation so that the opposite poles are adjacent, means for electrically connecting one pole of one of said cells with the casing, a spring switch connected with the opposite pole of another of said cells, conducting means connecting together the other opposite poles of said cells, and manually operative means on the edge of the casing for controlling the action of said spring switch.

7. A pocket electric light comprising an electrically conductive casing including two shallow matching shells adapted to be opened one from the other; and one of which carries on its side edge a socket for holding a miniature electric lamp having one terminal extended within the casing, a battery within the casing comprising a plurality of cells in side by side relation with their poles arranged in reverse relation so that the opposite poles are adjacent, means for electrically connecting one pole of one of said cells with the casing, a spring switch connected with the opposite pole of another of said cells, conducting means connecting together the other opposite poles of said cells, and manually operative means on the edge of the casing for controlling the action of said spring switch, said spring switch being adapted when unrestrained to engage the said lamp terminal, and said manually operative means having a non-conducting

member extending within the casing for engaging said spring switch and holding it out of contact with the lamp terminal.

8. A pocket electric light comprising a casing having opposite circular side parts one of which is adapted to be opened and at least one of these side parts being of electrically conductive material, a stem-forming electrically conductive lamp socket projecting radially from the edge of said electrically conductive casing part and adapted to receive an electric lamp with its central terminal exposed within the casing, a ring pivoted in the projecting lamp socket, a battery within the casing comprising a plurality of cells in side by side relation with their poles arranged in reverse relation so that the opposite poles are adjacent, means for electrically connecting one pole of one of said cells with said electrically conductive casing part, means for connecting together the adjacent opposite poles of the adjacent cells, a contact-making spring for automatically closing the circuit between the remaining pole of the remaining battery cell and the exposed central terminal of the lamp, and a manually actuatable member on the edge of the casing for holding the said contact-making spring out of contact with the lamp terminal.

Signed at New York city, in the county of New York and State of New York, this 3rd day of November, A. D. 1915.

BERNARD BENEDICT.
